SOUND REPRODUCING APPARATUS

Robert H. Dreisbach, Fort Wayne, Ind., assignor, by mesne assignments, to The Magnavox Company, Incorporated, Fort Wayne, Ind., a corporation of Indiana

Application February 5, 1938, Serial No. 188,894

7 Claims. (Cl. 179—100.4)

The present invention relates to sound reproducing apparatus, and more particularly to phonographs of the type that employ an electrical pick-up on the record and an electrodynamic sound reproducer for propagating the sound program.

An object of the invention is to provide a new and novel mounting for the sensitive sound reproducing elements of an electrical phonograph of the type using an electrodynamic loudspeaker, in which said sensitive apparatus is supported in a free floating manner so that vibrations produced in the cabinet by the sound reproducer will not be transmitted to said sensitive apparatus.

Another object of the invention is to provide a new and novel mounting for an electrical phonograph of the character described, in which the sound record supporting platen, its associated pick-up and the record platen driving motor are all supporting as a unitary structure in a free floating manner in a cabinet.

Another object of the invention is to provide a new and novel support for a sound record supporting platen, its driving motor and associated tone arm in a free floating position within a cabinet and in which an inertia supplying mass is provided upon the support to render the apparatus substantially static with respect to vibrations of the cabinet.

Another object of the invention is to provide a new and novel spring mounting for supporting a record carrying platen and an associated tone arm of an electrical phonograph in a cabinet, in which the spring mounting can be rendered temporarily inoperative to firmly secure said apparatus upon the cabinet for transportation.

Other objects and advantages of the invention will be in part pointed out and in part evident to those skilled in the art, from the following description taken in connection with the accompanying drawing, wherein there is shown by way of illustration and not of limitation preferred embodiments thereof.

In the drawing,

Figure 1 is a vertical sectional view of a sound reproducing phonograph of the type employing two electrodynamic loudspeakers,

Figure 2 is a fragmentary detailed view, in section, showing a preferred form of resilient mounting means constructed and arranged in accordance with the present invention,

Figure 3 is a modified form of the invention in which the weight of a thermionic tube amplifier

is associated with the apparatus to improve the operation of the resilient supporting means, and

Figure 4 is a view of the underside of the motor board of a phonograph showing a preferred form for an inertia mass supplying weight, as contemplated by the invention.

In the reproduction of sound from a record by electrical means of the character described, in which a modulated electric current is generated by a pick-up engaging a moving record, it is important that the pick-up needle follow the sound track and be free of any other extraneous force, such as vibrations which, as is well known, set up a false signal. One of the difficult problems with apparatus of this character is in providing a means that will prevent mechanical vibrations such as are produced by the phonograph driving motor and other associated apparatus from being transmitted to the sound record and pick-up device.

In the past others have provided various forms of shock absorbing resilient supports for the tone arms and driving motors of record supporting platens, which operate to absorb vibrations that might be transmitted between these elements. However, upon the adoption of electrodynamic sound reproducers in connection with phonographs of this character, there has been introduced a new problem, which in many respects is more difficult to overcome, for the reason that such a sound reproducer, when mounted upon or within a cabinet, sets up vibrations of considerable magnitude in the cabinet, which vibrations cannot be eliminated by the arrangements and expedients taught by the prior art.

To overcome the above problem and provide an electrical phonograph of the type employing one or more electrodynamic sound reproducers mounted in the same cabinet, the present invention contemplates a mounting of the sound record supporting platen, its driving motor and an associated tone arm upon a single support as a unitary mass that is secured upon the cabinet in a free floating manner, so that it will operate without being subjected to the vibrations set up in the cabinet structure by the electrodynamic sound reproducer. In extreme cases, and particularly where more than one sound reproducer are used in a single cabinet, or where a single large electrodynamic sound reproducer is used, the unit which comprises the more sensitive sound reproducing apparatus is provided with an additional weight or static inertia supplying mass which will react and cooperate with the resilient supporting means to effect an absorp-

tion of substantially all vibrations of the cabinet, and thus render the sound record and pick-up needle relatively immovable, except for that relative movement which is caused by the rotation of the record and the particular movements imparted thereto by the sound track upon the record.

In Figure 1 of the drawing the invention is shown as embodied in a phonograph of the type employing a tall cabinet 10, in the lower portion of which there is mounted two electrodynamic sound reproducing devices 11 that propagate as sound waves the signals generated by a pick-up device 12. Located in the upper part 15 of the cabinet 10 there is a sound record 13 with which the pick-up device 12 cooperates. The pick-up device 12 is mounted upon a swingable tone arm 14 that is pivotally secured upon a pedestal 15, and the record is shown as carried by a horizontally disposed record supporting platen 16 which is adapted to be driven by a motor 17. The pick-up 12 is shown as connected through a suitable cable to a terminal board 18, and extending downwardly from the terminal board 18 there is an additional cable 19 that serves to conduct the sound signal currents generated by the pick-up 12 to an amplifier 20 which functions, as is well understood, to amplify the signal currents and provide excitation for the electrodynamic sound reproducers 11 by means of conductors 21 and 22. Extending from the terminal board 18 there is also a lead 23 having a connector 25 at the end thereof, by means of which the phonograph may be connected to any suitable service outlet. The motor 17 is connected to the terminal board 18 by means of a cable 26, and it is adapted to be controlled by a suitable control unit 27, which is likewise connected to the terminal board 18 by means of a cable, as shown. The control unit 27, in addition to controlling the motor 17, also provides a means whereby the tone and volume of the sound reproducers 11 may be varied. Knobs 28 and 29 are associated with the control unit 27 for this purpose.

In practice it is customary to mount the sound reproducing devices 11 in a baffle 30 at the front of the cabinet, and in front of this baffle there is usually disposed an open grill work or other form of ornamentation 31 through which the propagated sound is projected. With this arrangement, and particularly where the sound signals reproduced are in the low frequency range, the electrodynamic sound reproducers 11 set up 50 a definite vibration in the cabinet walls. This vibration is partly due to the mechanical connection of the reproducers with the cabinet, and also because of the compressional wave vibrations set up within the cabinet at the back of the reproducers, which are often greatly accentuated by the resonance of the cabinet itself. To prevent transmission of these vibrations, which are set up in the cabinet 10 by the sound reproducing device 11, the present invention contemplates 55 a mounting of the pedestal 15 together with the pick-up 12 and its tone arm 14, and the sound record supporting platen 16 and its driving motor 17 upon a resiliently mounted supporting member 32, so that these elements will be held 60 in a relatively fixed operative relation with each other, and in a free floating manner with respect to the cabinet.

In Figure 2 of the drawing there is shown a preferred form of resilient mounting for the supporting member 32. As here shown, the cabi-

net 10 is preferably provided with a rectangular shelf-like projection 33 which extends around the inner walls of the cabinet at the upper part thereof. However, this shelf-like projection 33 might be provided by shelf-like members upon 5 opposite walls of the cabinet.

In the preferred arrangement the supporting member 32 is in the form of a rectangular motor board or panel upon which the record carrying platen 16 and the pick-up 12 are mounted, and 10 below which the platen driving motor 17 is mounted in suspended relation. With such a supporting member 32 there is preferably provided at its four corners a downwardly extending stud 34 which passes freely through an opening 35 in the shelf-like member 33. As here illustrated, the shelf-like member 33 is provided with countersunk portions 36 and 37 which extend respectively into the top and bottom sides of the shelf-like member 33 concentric with the opening 35. Disposed within these countersunk portions 36 and 37 of the opening 35 there are respectively conically wound spiral springs 38 and 39 which surround the stud 34. The spring 38 is adapted at its upper end to engage an enlarged head 40 upon the stud 34 and thus yieldingly hold this stud against downward displacement, and the spring 39 is adapted at its lower end to engage a securing means or nut 41 carried by the stud 34 to yieldingly resist any upward movement of the stud 34. In addition to functioning to prevent upward and downward movement of the stud 34, as above described, the springs 38 and 39, because of their conical construction and disposition within the counter- 35 sunk portions 36 and 37, also serve to resist any lateral movement of the stud 34, and as a result the motor board 32 will be yieldingly held upon the shelf-like supports 33 by the springs 38 and 39. As shown, the enlarged head 40 of the stud 34 may be drilled and threaded to receive a screw 42 for securing the supporting member 32 thereupon. At this point it will be noted that with such an arrangement the resilient supports may be fully assembled before the 45 supporting member 32 and its associated apparatus is placed in the cabinet 10. By properly designing the springs 38 and 39 with respect to resilience and the total mass carried by the support 32, and also adjusting the compression of the springs 38 and 39, it is possible with this arrangement to provide a resilient mounting for the more sensitive elements of the phonograph which will prevent the transmission of any vibrations from the cabinet to these elements. To 50 this end the present invention also contemplates a proportioning of the total mass of the resilient supporting apparatus, and the distribution of this mass with respect to the several resilient supporting means, so that such means will function uniformly, and thus insure a free floating of the more sensitive elements with respect to the cabinet. This is accomplished by securing a weight 43, as shown in Figure 1, preferably to the underside of the supporting member 32, as 55 will be more particularly pointed out hereinafter.

As an additional feature of the present invention, this figure of the drawing also shows a bracket 44 having a central opening 45, which is adapted to be placed over the extending end 70 of the stud 34 where a wing nut 46 may be threaded upon the end of the stud 34. The purpose of this bracket 44 is to provide a convenient means for securing the resilient support against damage when the phonograph is 75

in transit, and when in use with the nut 46 securely tightened upon the stud 34, the supporting member 32 will be drawn down firmly against the upper surface 47 of the shelf-like member 33, where the springs 38 and 39 will be rendered inoperative and protected against damage due to shock when the phonograph is in transit.

In Figure 3 of the drawing there is shown a modification of the present invention, wherein the weight of the more sensitive elements of the phonograph carried by the supporting member 32 is supplemented by the weight of a thermionic tube amplifier 48. When this expedient is resorted to, the weight 43 may be dispensed with. For the purpose of providing a distribution of this mass upon the supporting member 32, it will be understood that the position of the amplifier 48, with respect to the center of gravity of the entire mass, will be so positioned as to equalize the weight between the several resilient supporting means upon which the supporting member 32 is mounted. As shown, the amplifier 48 is suspended from the underside of the supporting member 32 by means of a bracket 49, but it will be understood that the amplifier 48 may be secured to the supporting member 32 in any other suitable manner.

In Figure 4 of the drawing there is illustrated the underside of a motor board or supporting member 50 having a static inertia mass supplying weight 51 secured upon the underside thereof. The motor board 50 in this instance is of elongated configuration and has a record driving motor 52 secured at one side of its center. A tone arm supporting pedestal, designated by the numeral 53, is mounted upon the upper side of the supporting member 50 over an opening 54 at one corner thereof through which pick-up conductors 55 extend. Because of the disposition of the record driving motor 52 at one side of the center of the motor board 50, and also because of the aperture 54 therein, the weight 51 is rounded out at one corner, as at 56, and at this end the weight 51 is also increased in cross-section, as at 57. This increase in cross-section of the weight 51 is to compensate for the off-center disposition of the motor 52 and the other apparatus upon the motor board, and thus provides a motor board having a uniformly distributed total weight between the four corners thereof.

While I have, for the sake of clearness and in order to disclose my invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In a sound reproducing phonograph, the combination of a cabinet, a sound reproducing device of the electrodynamic type mounted upon said cabinet, a sound record supporting platen having a driving motor, a tone arm having an electrical pick-up device adapted to swing over a record upon said platen and provide an exciting current for said electrodynamic sound reproducing device, a free floating support for said record supporting platen, its driving motor and said tone arm, said free floating support being mount-

ed upon resilient means carried by said cabinet, and a thermionic tube amplifier fixedly attached to and carried by said floating support, whereby said amplifier will be protected from vibrations set up in the cabinet structure by the electrodynamic sound reproducing device and the weight thereof will provide a stabilizing inertia supplying mass for said free floating support.

2. In a sound reproducing phonograph, the combination of a cabinet, a sound reproducing device of the electrodynamic type mounted upon said cabinet, a sound record supporting platen having a driving motor, a tone arm having an electrical pick-up device adapted to swing over a record upon said platen and provide an exciting current for said electrodynamic sound reproducing device, a free floating horizontally disposed panel upon which said record supporting platen, its driving motor and said tone arm are mounted, said panel being supported by shock absorbing means disposed between it and said cabinet, and means providing a stabilizing inertia supplying mass fixedly attached to said panel, the mass of said means being distributed substantially uniformly between said shock absorbing means and being of sufficient weight to cause said shock absorbing means to absorb all vibrations transmitted thereto by the cabinet.

3. In a sound reproducing phonograph, the combination of a cabinet, a sound reproducing device of the electrodynamic type mounted upon said cabinet, a sound record supporting platen having a driving motor, a tone arm having an electrical pick-up device adapted to swing over a record upon said platen and provide an exciting current for said electrodynamic sound reproducing device, a free floating horizontally disposed panel upon which said record supporting platen, its driving motor and said tone arm are mounted, said panel being supported at its corners upon spring means carried by said cabinet, and an open frame-like weight attached to the underside of said panel, said frame-like weight being adapted to extend in a rectangular path closely adjacent the sides and ends of said panel to distribute its weight substantially uniformly between the four corners of the panel and being of sufficient total weight to cause said spring means to absorb all vibrations transmitted thereto by said cabinet.

4. In a sound reproducing phonograph of the character described, the combination of a cabinet, a pair of spaced horizontally disposed shelf-like supports extending inwardly from opposite walls of said cabinet, a motor board disposed in overlapping relation with said shelf-like supports, said supports having openings therethrough at points corresponding to the corners of said motor board, a securing stud extending from each corner of said motor board through said openings and having a securing means at the other side of said shelf-like supports, and a spring means disposed about each of said studs between said shelf-like supports and said motor board and between said securing means at the other side of said shelf-like supports, said spring means being arranged in opposed relation about said studs and adapted to support said motor board in a floating position free of said shelf-like supports, whereby vibrations set up in the cabinet structure will not be transmitted to said motor board.

5. In a sound reproducing phonograph of the character described, the combination of a cabinet, a pair of spaced horizontally disposed shelf-like supports extending inwardly from opposite walls

of said cabinet, a motor board for mounting phonographic apparatus disposed in overlapping relation with said shelf-like supports, said supports having openings therethrough at points corresponding to the corners of said motor board, a securing means extending from each corner of said motor board through said openings and having a threaded means at the outer ends thereof, a spring means disposed about each of said securing means between said shelf-like supports and said motor board and between said threaded means at the ends of said securing means and said shelf-like members, said spring means being arranged in opposed relation upon said securing means and adapted to support said motor board in a floating position free of said shelf-like supports, and a static inertia supplying mass carried by said motor board supplementing the weight of the apparatus thereupon and cooperating with said spring means to prevent the transmission of vibrations from the cabinet to said motor board.

6. In a vibration absorbing support for sensitive sound reproducing apparatus, the combination of a cabinet having a fixed inwardly extending shelf-like member with an opening therethrough, an apparatus supporting member disposed within said cabinet in overlapping relation with said shelf-like member, a resilient shock absorbing means disposed between said shelf-like member and said apparatus supporting member, a stud upon said apparatus supporting member extending freely through the opening in said shelf-like member, a threaded securing means at the outer end of said stud, and a second resilient shock absorbing means disposed between the other side of said shelf-like member and said threaded securing means cooperating with said

first resilient shock absorbing means to provide a free floating support for said apparatus supporting member, the securing means at the outer end of said stud being adjustable to vary the degree of compression of said two resilient shock absorbing means, whereby the resilience thereof may be adjusted to vary the shock absorbing characteristics thereof.

7. In a vibration absorbing support for sensitive sound reproducing apparatus, the combination of a cabinet having a fixed shelf-like member with an opening therethrough, an apparatus supporting member disposed within said cabinet in overlapping relation with said shelf-like member, a resilient shock absorbing means disposed between said shelf-like member and said apparatus supporting member, a securing means for said apparatus supporting member extending freely through the opening in said shelf-like member, a threaded means at the end of said securing means, and a second resilient shock absorbing means disposed between the other side of said shelf-like member and said threaded means and cooperating with said first resilient shock absorbing means to provide a free floating support for said apparatus supporting member, said securing means being extended out beyond said threaded means, and a clamping member having a central opening adapted to be positioned over the end of said securing means and tightened thereupon by a second threaded means to compress said first resilient shock absorbing means and firmly secure said apparatus supporting member against said shelf-like member as when the cabinet is in transit.

ROBERT H. DREISBACH.
